UNITED STATES PATENT OFFICE.

WILLIAM HENRY BRAIM, OF VANCOUVER, CANADA.

RAILWAY-SWITCH.

SPECIFICATION forming part of Letters Patent No. 751,254, dated February 2, 1904.

Application filed May 25, 1903. Serial No. 158,753. (No model.)

To all whom it may concern:

Be it known that I, WILLIAM HENRY BRAIM, a citizen of the Dominion of Canada, residing at the city of Vancouver, in the Province of British Columbia, Canada, have invented a new and useful Improvement in Railway-Switches, of which the following is a specification.

The object of this invention is to provide means whereby the switch-blade of a street-railway junction may be operated from the platform of an approaching car by the motor-man without the necessity of his leaving his position, and my effort has been to provide a mechanism that shall be simple and direct in its action, that shall form no obstruction to the ordinary street traffic, that shall be readily applicable to existing plants, and that shall not be liable to derangement in use. I have further endeavored to avoid the necessity for the operative mechanism being any considerable distance from the switch. The particular construction by which these advantages are attained is fully set forth in the following specification and illustrated in the drawings which accompany it.

Figure 1 is a plan of the switch-blade having my attachment; Fig. 2, a longitudinal section on the line *a a* in Fig. 1; Fig. 3, a plan, to an enlarged scale, of the **L**-lever and its connection to the switch-blade; Fig. 4, a similar view of the spring designed to hold the blade in either position for main line or branch; Fig. 5, a vertical section through the box in closing the **L**-lever, showing the lever, &c., in elevation. Figs. 6 and 7 are longitudinal vertical sections through the mechanism by which the **L**-lever is actuated for either the branch or the main line; Fig. 8, a cross-section on the line *b b* in Fig. 7; Fig. 9, a detail of the connection of the branch and main line mechanisms, so as to be coöperative one with the other; and Fig. 10, a cross-section on the line *c c* in Fig. 6.

Throughout the drawings the rail is indicated by *R*, the ties by *T*, and the switch-blade by *S*.

The switch-blade *S* is connected by a rod 2 and link 3 to the short arm 4 of an **L**-lever 5 pivotally mounted on a pin 5, secured in the

bottom of a box or casing 6, which incloses the lever and its attachments, and is fastened to the ties or road-bed in any suitable manner and to the rail *R* by a stay 7, the box being provided with a removable cover 8 at the approximate level of the surface of the road. To the long arm 9 of the **L**-lever is connected the rod 10 from the car-operated mechanism to move the switch-blade one way or the other, as required, and to the pin 11 of this connection is attached one end of a tension-spring 12, the other end of which is connected by a link 13, curved to pass round the boss of the **L**-lever, to a pin 14 immediately behind the axis of rotation of the **L**-lever and in the center line of its oscillation. The effect of this spring is to retain the **L**-lever and its connected parts in either extreme of its movement, as clearly shown in Fig. 4.

The rod 10, by which the movement of the **L**-lever and switch is effected, extends a convenient distance along the track parallel to the rail, and at its farthest end is threaded to receive a member 15, slideable in a guide 16 and having a portion 15^a projecting upward through a longitudinal slot 17 of the guide. This upwardly-projecting member 15^a is shaped to offer engagement toward the appliance operated from the car-platform by which it is designed to be moved and which will be described later. A short distance farther along the track from the point of the switch-blade is a guide-frame 18, similar to 17 and provided with a slot 19, but having in addition at its farther end depending portions 20, between which is mounted a sheave 21. The slideable member 22 of this guide has secured to it a wire rope 23, which passes forward round the sheave 21 and returning is secured to the screwed end of the rod 10 by means of a nut portion 25, threaded on the screwed end of the rod 10 and provided with oppositely-projecting pins 26, on which the ends of an elongated **U**-shaped member 27 are sprung and secured with split pins. The end of the wire rope 23 passes through an aperture in the bend of the **U** and is secured by a knot in a washer 28. The connection thus made is rotatable as a swivel when adjustment is required. The connection between the two 100

slidable members 15 and 22 is so adjusted that as one is at one end of its slot the other is at the opposite end of the other slot, and they are coöperative together, so that when 15 5 pushes the rod 10 and, by means of the L-lever 9, 4 sets the switch-blade S into position for the branch it also by means of the wire-rope connection over the sheave 21 pulls the slidable member 22 toward the direction of 10 approach. Conversely, when 22, being at the end of approach of a car toward the junction, as indicated by the arrow f, is moved along the slot the rod 10 and its attached and connected parts are pulled back and the switch-blade set 15 for the straight track. The upward projections 15^a 22^a of the slidable members are engaged and operated by the lower end 30^a of a pivotally-mounted lever 30 on the car-platform 31, which may be lowered by the motorman by 20 means of the handle 32, forming an upward extension of the lever 30. The end 30^a being widened to insure engagement will catch 15^a or 22^a, as desired, and will as the car moves forward pull with it the slidable member and its 25 connected mechanism to operate the switch-blade one way or the other, according to which member is engaged, and when the slidable member approaches the end of the slot or limit of its movement toward the switch 30^a is pushed 30 off its engagement by the raised portion or incline 35 on the upper surface of each guide member. A smooth track 36 is provided for the trailing end 30^a at the approach to and between the guide-frames, and to further insure 35 smooth and steady action I may provide the end of 30 with a light wheel or roller. The catch-lever 30 may be retained clear of the track and and out of action by a spring 33, or a catch may be furnished to hold the lever 32 40 in the out-of-action position.

The rod 10 is protected by a pipe 37, through which it is passed and which extends between and rests on suitable supports on the L-lever box and the proximate guide-frame.

45 The device is shown as secured to timbers 38, resting on the ties T of the track, which will afford a firm and inexpensive means of fixing it.

The operation of the mechanism hardly 50 requires explanation further. As a car approaches the junction the motormen lowers the lever 30 30^a to engage either 15^a or 22^a, as he requires, to take the junction or proceed on the straight track, and the slidable block 55 engaged is moved along its slot to effect the desired movement, being automatically disengaged at the limit of its movement by the raised portion 35 at the end of the slot, and the switch-blade is retained in the position it 60 is moved to and recoil prevented by the spring 12 in the lever-box.

The L-lever may be made with the additional short arm, as indicated by dot-and-dash lines in Figs. 1, 3, and 5, so that one pattern

may serve for either right or left hand 65 branches.

The device is extremely simple in its manufacture, its application, and its working, and there is no part exposed to undue wear or liable to derangement, while the threaded connections to the rod 10 afford every facility for independent adjustment. The extended movement of the operative slidable members 15 and 22 and the considerable ratio of the levers 9 and 4, through which that movement is communicated to the switch-blade, make the effort necessary to throw the switch extremely light. Efficient drainage being provided, no difficulty will be experienced with silt or dirt, as the only place where such might be troublesome— 75 viz., in the grooves of the guide—is swept clear by the slidable members at every movement of the switch.

I do not desire to be confined to the particular construction of the parts or means of 85 connecting the same, as such may be somewhat modified to suit the requirements of manufacture; but

What I claim as new, and desire to be protected in by Letters Patent, is— 90

1. In a device of the class described; two guide-frames situated a short distance apart in the line of approach to the switch, blocks slidable endwise in such guides and having portions upwardly projecting through elongated slots in the upper sides of the guideways such upward projections being designed to be engaged by suitable members depending from the car-platform, means for connecting the two slidable blocks so as to be oppositely movable 95 in relation to each other, and means for connecting the blocks to the switch so that the forward movement of one block operates the switch for the main line and the other for the branch, substantially as described. 100

2. In a device of the class described having a pivotally-mounted L-lever by which the switch-blade is operated; a means to retain the mechanism in either extreme position comprising a tension-spring one end of which is connected toward the end of one of the levers of the L and the other end to a position on the opposite side of the pivot-pin of the L-lever and in the center line of the lever's oscillation. 110

3. In a switch-operating mechanism; a pivotally-mounted L-lever having a tension-spring to retain it in either extreme of its movement, a link connection from one arm of the L to the switch-blade, a rod connected to the other arm and extending along the track, a block adjustably secured to the rod and slidably in a guide and having a portion projecting above the road-surface through an elongated slot in the upper side of the guide, a raised portion on the upper surface of the guideway at the end of the slot toward the switch, a second slidable block and guide- 115 120 125

frame a short distance from the foregoing toward the direction of approach, a sheave rotatably mounted in the farther end of the second guide-frame, and a flexible connection 5 from the second guide-block round the sheave and back to an adjustable connection on the aforementioned rod.

In testimony whereof I have signed my name to this specification in the presence of two subscribing witnesses.

WILLIAM HENRY BRAIM.
